(57) **CLAIM**

The ornamental design for an aircraft parking brake handle,
as shown and described.

DESCRIPTION

The patent or application file contains a least one drawing
executed in color. Copies of this patent or patent application
publication with color drawing(s) will be provided by the
Office upon request and payment of the necessary fee.

FIG. 1 is a front perspective view of an aircraft parking brake
handle;

FIG. 2 is a front view of an aircraft parking brake handle with
surrounding environmental structure removed for clarity of
disclosure.

FIG. 3 is a back view of an aircraft parking brake handle;

FIG. 4 is a first side view of an aircraft parking brake handle;
FIG. 5 is a second side view of an aircraft parking brake
handle; and,

FIG. 6 is a top view of an aircraft parking brake handle, the
bottom of the aircraft parking brake handle is not illustrated as
it forms no part of the claimed design.

The broken lines illustrate structures that form no part of the
claimed design.
